VAPOR STOVE

Application filed October 14, 1927. Serial No. 226,074.

Objects of the improvements are the production of a vapor burning device of relatively simple, convenient and durable construction and efficient operation adapted to be used for the heating of living apartments and also for various other purposes, in which the tank for liquid fuel, pressure generating means therefor, vaporizer, manifold and burners are so constructed and arranged that they form a composite unit which may be easily inserted in and removed from a stove frame and may be employed in connection with various external frames or housings or without such casings and with or without other means for supporting cooking or heating vessels or otherwise applying or distributing the heat of the burners.

Other objects and advantages will appear from the following drawings and the following description.

In the said drawings, Figure 1 is a front view of an indoor heating stove casing with the unit comprising tank, vaporizer, manifold and burners, pressure device and their accessories mounted therein, embodying the improvements;

Fig. 2 is a view of the right hand end thereof;

Fig. 3 is a front elevation of the said unit removed from the stove casing; and

Fig. 4 is a plan thereof.

The stove frame or casing comprises top 1, sides 2 and 3, back 4, lower front plate 5, inwardly curved front deflector plate 6 hinged to the plate 5 at 7, inwardly inclined inner sides 8 and 9 and bottom end bars 10 rigidly connected with feet 10a and with supporting bars 10b running across the open bottom of the frame from end to end. Suitable cold handles 2a and 3a are hinged near the top of the sides 2, 3, for lifting and carrying the drum casing and tray, and grids 11 of refractory material—in this case four in number—are mounted within the drum above the deflector plate and back of the rear upper edge thereof to receive the combustion from the burners and produce a heat-radiating glowing member or front. The details of construction and arrangement of these parts are not essential features of the present im-

provements. The hinged inwardly and upwardly curved deflector plate 6, however, is a feature, and is adapted to be turned outwardly and downwardly to open the drum and give access to the burners and other parts therein for lighting or other purposes. In normal position it is supported by curved bosses 12 in the sides 9, and the grids 11 are supported by an open shelf 13 extending across the stove at the inner edge of said deflector.

The fuel supply and combustion unit comprises a tank 14, burners 15, vaporizing tube 16, vaporizing burners 17, manifold 18, pressure pump 19, supporting head 20, and connections. These parts are all rigidly connected to form a complete unit which may be placed in a stove casing or other frame or removed therefrom, as a unit, transported and handled or used in various ways.

The tank 14 is connected with the supporting head 20 by means of a strap or band 21 secured around one end and brackets 22 fixed to said band and to the head. It is also connected to the said head by means of the drip pan 23 which is mounted thereon by means of supports 25 and 26, extending outwardly from the band 21 and from the band 24 at the opposite end of the tank and having laterally extending arms 27 and 28, the extremities of which are turned over and grasp the side edges of said pan, the pan having a downwardly turned end 29 secured to the said supporting head.

The member comprising the vaporizing tube, manifold, burners, and vaporizing burners consists of a hollow tubular casting 30 with a long tubular member 31 on which the hollow burners 15 are formed and a shorter member 32 of the manifold 18, a branch tube 33 communicating with 31 to supply vaporized fuel to the vaporizer heating burners 17 thereon and the vaporizer tube 16 extending through the supporting head 20 and having its opposite reduced end 34 extending through and fixed in the laterally extending circular head and shield 35. The said casting has feet 36 at one end and 37 at the opposite end secured to the drip pan, so that the unit just described is rigidly

mounted thereby on the tank and rigidly connected with the supporting head. A central filling hole is provided in the tank and this hole is securely closed by means of a cap 39.

5 Fuel from the tank passes through the T connection 40, the fuel tube 41 and the union 42 to the vaporizing tube 16 and thence through the manifold 18 to the main burners, 10 a needle valve 43 controlled by the handle 44 regulating the passage of vaporized fuel into the manifold or shutting it off altogether, an adjustable shutter 45 on the manifold being provided to regulate the admission of air thereto through the air intake port 46. Fuel to supply the vaporizer heating burners 17, for initial heating, passes through the connection 40, the pipe 47 controlling valve 48, operated by the wheel 49 15 and through the pipe 47a. During the normal operation of the main burners, however, the vaporizing burner receives its fuel through the branch pipe 33, the valve 48 being closed, and in this manner the heating 20 of the vaporizer tube is automatically regulated to meet the needs of the burner, since the volume of vaporized fuel supplied to the vaporizer heater depends upon the amount of such fuel admitted to the main burners 25 30 and the combustion of the said heater is therefore increased and reduced with the combustion of the main burners.

All burners are preferably provided with plugs 38 having numerous orifices therein for 35 the passage of fuel.

Air pressure is communicated from the pump 19 to the tank 14 through pipe 50 having a valve 51 thereon controlled by the wheel 52, and the pipe 50a to the connection 40, and the pressure in the tank is indicated by the gage 53 communicating with the main fuel conduit 41 at the union 42.

In the present case, the end of the tank opposite the supporting head is provided with legs 54 on which it may be supported when in upright or filling position, the end of the drip pan 23 acting as the third leg when the tank is in this position. These legs also serve in the illustrated application to space 50 the unit from the inner end of the stove casing.

In the operation of the device the tank is first filled and placed under pressure by means of the pump, liquid fuel is then admitted to the vaporizer heater to heat the fuel in the vaporizer, the heater is then lighted and fuel then admitted from the vaporizer to the manifold by means of the needle valve and the main burners lighted. When main 55 60 65 burners are in operation the liquid fuel to the vaporizer heater is then shut off, and the said heater supplied with fuel from the main burner tube. Combustion is regulated throughout the operation of the stove by means of the needle valve.

In the illustrated application of the improvements the unit, including tank vaporizer, manifold and burners is passed into the stove casing and supported therein by the bottom members 10, 10b, and may be readily removed therefrom for filling. This particular arrangement, however, is not essential, and the stove casing may be constructed and arranged to be lifted off the fuel and combustion unit or the fuel and combustion unit may be permanently mounted in the bottom of the casing and the upper part of the casing made removable. Other constructions and arrangements for housing the unit may also be employed.

As before noted, the tank and burner unit may be used in various ways, and may be made in various sizes and shapes and with any desired number of burners. Thus it may be passed under an ordinary grate for the purpose of heating or cooking food or other substance in any ordinary way. The unit is in effect a portable stove and may be used indoors or out for all cooking and heating purposes. The unit may also, if desired, be provided with a base of its own and with cooking grids or other supports, for utensils or containers to be heated, mounted upon said base or upon the ground. It will also be apparent that various changes in the construction and arrangement of the parts herein shown and described may be made without departing from the scope of the improvements.

In the illustrated embodiment of the improvements the burners are located below the grid of refractory material and are spaced a short distance therefrom and the hinged deflector plate protects the burners from drafts and directs currents of air passing up from the open bottom of the stove to said burners and through said grid along with the burning gases of the burner combustion so that a large volume of heated air passes from the upper part of the stove and heat is also radiated from the grid. The supporting base of the fuel and combustion unit serves to close the end of the stove when the said unit is inserted therein, as well as to unite the elements of said unit and maintain them in their proper positions and relations at all times. There is thus provided a heating stove of efficient and convenient form and compact and attractive appearance.

What I claim is:

1. A fuel and combustion unit for heating or other stoves comprising a horizontally disposed liquid fuel tank, a multiple burner horizontally disposed above and spaced from said tank, an elongated vaporizing retort adjacent said burner, a manifold between said retort and burner and in communication with both, a vaporizer heating burner below said retort and conduits connecting said tank with said retort and said heating burner, and a

- vertically disposed supporting head on which all of said parts are rigidly supported in operative relation.

2. A fuel and combustion unit for heating or other stoves comprising a horizontally disposed liquid fuel tank, a multiple burner horizontally disposed above and spaced from said tank, an elongated vaporizing retort adjacent said burner, a manifold between said retort and burner and in communication with both, a vaporizer heating burner below said retort and conduits connecting said tank with said retort and said heating burner, and a vertically disposed supporting head on which all of said parts are rigidly supported in operative relation, said unit also comprising a drip pan beneath said burners spaced therefrom and from the tank and rigidly connected with both.

20 3. A fuel and combustion unit for heating or other stoves comprising a horizontally disposed liquid fuel tank, a multiple burner horizontally disposed above and spaced from said tank, an elongated vaporizing retort adjacent said burner, a manifold between said retort and burner and in communication with both, a vaporizer heating burner below said retort and conduits connecting said tank with said retort and said heating burner, and a vertically disposed supporting head on which all of said parts are rigidly supported in operative relation, said unit also comprising a drip pan beneath said burners spaced therefrom and from the tank and rigidly connected with both and also with said head and being supported at a point spaced from said head upon said tank.

30 4. A fuel and combustion unit for heating or other stoves comprising a horizontally disposed liquid fuel tank, a multiple burner horizontally disposed above and spaced from said tank, an elongated vaporizing retort adjacent said burner, a manifold between said retort and burner and in communication with both, a vaporizing heating burner below said retort and conduits connecting said tank with said retort and said heating burner, and a vertically disposed supporting head on which all of said parts are rigidly supported in operative relation, said unit also comprising a pressure pump mounted on said head and in valve controlled communication with said tank.

40 5. A fuel and combustion unit for heating or other stoves comprising a horizontally disposed liquid fuel tank, a multiple burner horizontally disposed above and spaced from said tank, an elongated vaporizing retort adjacent said burner, a manifold between said retort and burner and in communication with both, a vaporizer heating burner below said retort and conduits connecting said tank with said retort and said heating burner, and a vertically disposed supporting head on which all of said parts are rigidly supported in operative relation, said unit also including spacing members extending laterally beyond the end of said tank opposite the head adapted to space the unit from the inner wall of a stove casing and also adapted to act as a support for said unit when the same is placed in upright position.

50 Witness my hand this 10th day of October, 1927, at the city of Milwaukee, in the county of Milwaukee, State of Wisconsin.

60 WALTER C. LINDEMANN.
